UNITED STATES PATENT OFFICE.

LEWIS LAYMAN, OF WESTFIELD, NEW YORK, ASSIGNOR TO E. P. WHITNEY, OF SAME PLACE.

LOCK.

Specification of Letters Patent No. 30,606, dated November 6, 1860.

To all whom it may concern:

Be it known that I, LEWIS LAYMAN, of Westfield, in the county of Chautauqua and State of New York, have invented a new 5 and useful Improvement in Reversible Slides for Locks and Latches; and I do hereby declare that the following is a full, clear, and exact description of the same, reference being had to the annexed drawings, making a 10 part of this specification, in which—

Figure 1, is an interior view of a lock with my invention applied to it. Figs. 2 and 3, horizontal sections of the same taken in the line *x*, *x*, Fig. 1. These views shows the 15 latch in two different positions.

Similar letters of reference indicate corresponding parts in the several figures.

This invention relates to an improvement in that class of locks and latches which are 20 provided with reversible slides for the purpose of adapting one and the same lock to either a right or left-hand door without inverting the former.

The invention consists, in a novel and im- 25 proved construction of the "hub" by which the slide is actuated, whereby the slide is held firmly in proper position, the hub made to fit snugly in the lock or latch case, and the slide readily adjusted or reversed in po- 30 sition when required.

To enable those skilled in the art to fully understand and construct my invention I will proceed to describe it.

A, represents the case of a lock and B, the 35 bolt, the latter being fitted in the case and arranged in the usual way.

C, represents the side latch, the outer end *a*, of which is beveled at one side as shown at *b*, in order that the side may, on shutting 40 the door be forced within the case as the beveled side *b*, comes in contact with the nosing A'. The end *a*, of the slide is attached to its body or shank *c*, so as to form a shoulder *d*, at each side of the shank of equal width as 45 shown in Figs. 2, and 3, and the inner end of the body or shank *c*, is provided with a yoke or fork *D*, the ends of which have heads or cross pieces *e*, *e*, which project at

equal distances from each side of the prongs of the yoke or fork *D*. 50

E, represents the hub of the lock which is provided with four arms *f*, said arms projecting from the hub *E*, in pairs from opposite sides of the hub. The arms *f*, embrace the prongs of the yoke or fork and 55 either pair bear against the heads or cross pieces *e*, *e*, as the hub is turned to throw back the slide latch.

The body or shank *c*, of the slide adjoining the end *a*, is provided at each side with 60 a projection *g*, against either of which a spring *F*, bears, said spring having a tendency to keep the slide *C*, forced outward.

The slide *C*, it will be seen may be readily reversed so as to convert the lock into a 65 right or left-hand one as occasion may require, both sides of the slide being precisely alike so that the operation of the slide will be the same when adjusted in either position.

The hub *E*, provided with its four arms *f*, 70 serves to retain the slide *C*, in proper position and the hub is made to fit snugly in place and is not liable to be casually displaced in opening the lock case to reverse the slide, a contingency of frequent occurrence in adjusting the reversible slides as 75 hitherto arranged.

I am aware that reversible slide latches have been previously used for converting a lock or slide latch into a right or left-hand 80 one at will, and I therefore do not claim broadly such device; but

I do claim as new and desire to secure by Letters Patent—

The employment or use of a hub *E*, pro- 85 vided with four arms *f*, projecting in pairs from opposite sides of it, in connection with a reversible slide *C*, having the prongs of its yoke or fork provided with heads or cross-pieces *e*, *e*, the hub being applied to 90 the yoke and all arranged essentially as and for the purpose set forth.

LEWIS LAYMAN.
